UNITED STATES PATENT OFFICE

2,554,867

HUMIDIFIER

Bertram M. Mills, Pawtucket, R. I., assignor to
The Standard Engineering Works, Pawtucket,
R. I., a corporation of Rhode Island

Application April 9, 1949, Serial No. 86,515

6 Claims. (Cl. 261—91)

1
This invention pertains to humidifiers of the type in which cold (unheated) water or other liquid is atomized or reduced to the form of a vapor by mechanical or equivalent means, the finely divided moisture particles then being adiabatically absorbed by the air into which the vapor is delivered. While, for convenience in illustration, the invention is here disclosed as embodied in apparatus of the industrial type (such as is used for moistening the air in textile mills, etc.), it is equally useful when embodied in a humidifier, whether or not portable, for use in homes or offices and wherein the atomizing elements are usually housed in a cabinet or casing of ornamental external appearance. The invention disclosed constitutes an improvement upon the device disclosed, for example, in the patent to Mills, No. 1,815,951, July 28, 1931.

Humidifiers, such as shown in the above patent, have proven very effective and have gone into extensive commercial use. However, it has been noted that the moisture laden air current does not emerge from the device in a way to insure immediate contact with as large a volume of the room air as is desirable for complete absorption and, thus, under certain atmospheric conditions, moisture in the form of minute droplets may be deposited on surrounding surfaces. Furthermore, as respects humidifiers designed for home or office use, it has been noted that they have a tendency to emit an undesirable noise, not particularly loud but which is objectionable to some people. Careful study of apparatus built in accordance with the above patent appears to indicate that there is a very substantial loss of energy and capacity due to the friction of the flowing moisture laden air against the inner surface of the casing. The constructions shown in said patented device is such as to create a pronounced swirl or rotating current in the moisture laden air which emerges from the vapor-creating means and this swirl probably accounts for the noise.

It has now been discovered, as the result of extended practical experience and after long experimentation, that greatly improved results are obtainable by fixing the vanes which are impinged by the liquid and which reduce the latter to the vapor form, at a very definite angle, within a very limited range.

It has also been noted that unless the under-surface of the atomizing disk be located very accurately with reference to the atomizing vanes, the effectiveness of the device is greatly re-

duced. The possibility of inaccuracy of relative location of these parts is present in the device of the above patent by reason of the fact that the apparatus (at least that of the industrial type) is usually shipped knocked down and is erected at the place of use, sometimes by persons not well qualified to set up the apparatus with the requisite accuracy.

2
One object of the invention is to provide a humidifier of the general type disclosed, for example, in the above patent, but so improved as to insure a high velocity of delivery and an improved quality of the moist air delivered, with consequent better distribution and more thorough absorption of the moisture by the ambient air. A further object is to provide a humidifier of the above type so designed as to reduce the friction losses within the casing of the apparatus, thus increasing the capacity of the device. A further object is to provide a humidifier so designed as to reduce the tendency of the moisture laden air, emerging from between the atomizing vanes, to take up a rotating or swirling motion within the casing. A further object is to provide a humidifier so designed that the moisture laden air emerges in a substantially uninterrupted stream. A further object is to provide a humidifier whose parts are so designed that, in assembling them, the water-distributing surface of the atomizing disk must be located accurately with respect to the atomizing vanes. A further object is to provide a humidifier of the above type wherein the atomizing vanes are so designed as to provide approximately radial channels which terminate outwardly beyond that peripheral surface of the cover member of which the vanes constitute integral parts. A further object is to provide a humidifier wherein the atomizing vanes are disposed at angles such as have been found to result in the optimum atomizing action. Other and further objects and advantages of the invention will be pointed out in the following more detailed description and by reference to the accompanying drawings where-

45 in:

Fig. 1 is a diagrammatic side elevation of an industrial installation embodying the present invention;

Fig. 2 is a diametrical vertical section, to larger scale than Fig. 1, showing the construction of the atomizer, per se;

Fig. 3 is a vertical section on the same plane as Fig. 2, but to larger scale, showing the atomizing disk and the cover member with its atomizing vanes;

Fig. 4 is a plan view of the parts shown in Fig. 3, a portion of the cover being broken away;

Fig. 5 is a fragmentary plan view, to larger scale, illustrating a desirable angular arrangement of the vanes;

Fig. 6 is a fragmentary vertical radial section, to larger scale, substantially on the line 6-6 of Fig. 1, through the upper portion of the side wall of the fluid receptacle and the lower part of the case; and

Fig. 7 is a fragmentary diametrical section through the central portion of the atomizing cone and disk.

Referring to the drawings, the numeral 1 designates an atomizing apparatus of industrial type embodying the present invention. As illustrated, the atomizing mechanism is carried by a bracket 2 designed to be secured to a vertical surface, for example the wall of a mill or a supporting column. Liquid, usually water, is supplied through a pipe 3, preferably passing through a strainer 4 and a pressure-reducing valve 5 to a float valve reservoir F from which it flows by gravity to the fluid receptacle of the humidifier. An overflow pipe 6 may be provided leading to a suitable discharge point. A flexible electrical conductor 7 extends from the motor of the humidifier to a conveniently located control box 8 which receives current through a conductor 9 from a suitable source of supply.

Referring to Fig. 2, the humidifier of the present invention comprises a shallow basin-like receptacle 10, usually a metallic casting (although moulded synthetic plastic is sometimes desirable), having a cylindrical side wall 11 provided with screw-threaded holes 12 and 13 to receive the ends of the supply and overflow pipes, respectively. The upper part of the side wall is provided with spaced upstanding lugs 11a providing between them the large windows 14 constituting air inlet openings.

At the center of the receptacle the latter is provided with an annular upstanding wall 15, usually integral with the bottom of the receptacle, defining a central well 16 to which fluid from the main body of the receptacle may flow through openings 17a in the lower part of the wall 15.

A bottom casing member 17, usually of sheet material, is supported on the upper edges of the lugs 11a. As shown in Fig. 6, the part of the lower casing members 17 rests upon the upper edges of the lugs 11a, the material of the bottom casing member then extending vertically down and then horizontally inward at 18a and then extending downwardly and inwardly to form the truncated, conical, annular guard member 19, the lower edge of which terminates in a plane approximately midway of the height of the windows 14, the large opening bounded by said lower edge defining a passage for air.

The upper part of the bottom casing member 17 is shaped to provide a cylindrical flange 20 within which is snugly fitted the lower part of the upper casing member 21, usually of sheet metal, tapering upwardly and terminating at its upper end in a cylindrical annular flange portion 22 defining the axial delivery opening 23. As illustrated in Fig. 1, a discharge elbow 24 may be fitted into the flange 22. This elbow is rotatable with respect to the casing 21 so as to provide for adjustment of the direction of vapor delivery, if desired. However, the elbow 24 may be omitted so that the vapor-laden air will be discharged directly upward through the opening 23.

A cover member 25 (Fig. 3), usually of sheet

metal, is arranged above the receptacle 10, the cover comprising the flat horizontal central portion 26 and having the cylindrical downwardly depending skirt portion 27 whose lower edge 28 rests upon the horizontal portion 18a of the bottom casing member 17. The part 26 of the cover constitutes a support for the motor M which is arranged with its shaft vertical. This motor has a heavy base plate 29 (Fig. 2). Three cushion members are interposed between the base plate and the upper surface of the part 26 of the cover, and depending pins 30 fixed at their upper ends in plate 29 pass down loosely through openings 31 in the part 26 (the latter being imperforate except for these openings and the central opening which receives the motor shaft), thus providing a three-point suspension for the motor, as more fully described in the patent to Mills, No. 1,604,295, dated October 26, 1926.

The shaft 32 of the motor extends down through a central opening in the part 26 of the cover and is fixed within an axial bore 33 in the hub 34 of the water-lifting cone 36. This hub 34 is integral with the depending, downwardly tapering, truncated conical, water-lifting cone 36. Preferably, though not necessarily, the outer surface of this cone 36 is provided with helical grooves 37 to assist in lifting the water from the reservoir, as more fully described in the patent to Mills, No. 1,537,650, dated May 12, 1925. The atomizing disk 35, having a central aperture for the reception of the hub 34, is secured to the upper surface of the cone 36, for example, by pins or screws. This disk may be of metal, but is preferably of a plastic material which is not corroded by the liquid. If the atomizing disk be of a plastic material, it is preferably of the order of $\frac{1}{8}$ inch thick. Preferably this disk is flat, having smooth, parallel, horizontal upper and lower surfaces.

Preferably a sleeve 38 is fixed within the lower part of the bore 33, the upper edge 39 of this sleeve constituting a stop for the lower end of the motor shaft. The sleeve 38 may have a drive fit in bore 33 and is of such length that the stop shoulder 39 is at a predetermined definite distance from the lower surface of the disk 35. Thus, when the parts are assembled and with the motor supported on the cover, and with the hub 34 pushed up onto the motor shaft until the shoulder 39 engages the lower end of the shaft, the lower surface of the disk 35 will necessarily lie in a predetermined plane with reference to the lower edge 28 of the cover.

The cylindrical skirt portion 27 of the cover is vertically slotted (but leaving a ring of the material intact above and below the slits) and the metal intervening between the slits is twisted at top and bottom to provide the atomizing vanes 40 (Figs. 4 and 5). These vanes are spaced apart and define the side walls of passages 41 extending outwardly from the interior of the cover and through which the moisture-laden air is expelled. As illustrated in Figs. 3 and 5, the metal which joins the vanes 40 to the parts 27 and 28 is so twisted that the outer edges E of the vanes are spaced from the outer peripheral surface S' of the skirt 27, while the inner edges of the vanes are likewise spaced from the inner peripheral surface S² of the skirt. Preferably the vanes extend outwardly beyond the surface S' a distance of approximately $\frac{1}{8}$ inch and are of a radial width of approximately $\frac{1}{4}$ inch and extend inwardly beyond the surface S² approximately $\frac{1}{8}$ inch. The inner edges of these vanes are spaced

from the outer edge of disk 35 a distance P which varies with the size of the apparatus, as hereinafter more fully described. As shown in Fig. 5 each vane is substantially flat throughout its effective length, although each vane is integrally joined at its upper and lower ends respectively, to the parts 27 and 28 by a twisted portion of the metal.

Each vane 40 is disposed at an angle to a radial line drawn through the vertical inner edge 42 of that face of the vane which is impinged by the liquid centrifugally expelled by the disk, rotating in the direction of the arrow R (Fig. 4), as illustrated in Fig. 5, this angle being the angle A between the surface of the vane and the radial line X-Y.

To the undersurface of the disk 35 air-impelling blades 43 (Fig. 4) are secured. These blades may vary in number according to the size of the apparatus, for example from 3 to 6. These blades may be of sheet metal or they may be integral with the disk if the latter be of a molded plastic. As illustrated, each blade makes an acute angle with a radius through its outer corner 44. This angle B (Fig. 4) between the plane of the blade and a radial line T-W may for example be 20°, although it may vary, in accordance with the size of the apparatus, from 20 to 27°, for example.

Specific examples of desirable dimensional relationships, but without intent to limit the invention thereby, are given in the following table:

Disk Diameter	No. of Fan Blades	Angle:		P	R. P. M.
		A	B		
7 ¹⁵ / ₁₆ "	3 or 6	63°±3½°	27°	1364"	3,150
9"	3	63°±3½°	20°	532"	3,450
10 ³ / ₈ "	6	63°±3½°	20°	36"	3,450

P = the distance between the inner edges of the vanes 40 and the outer edge of the disk 35.

When the parts are assembled (Fig. 2) with the lower end of the motor shaft in contact with the shoulder 39, the lower surface 45 of the disk 35 is disposed midway between the upper and lower ends of the vanes 40, this having been found by experience to be the point at which optimum results are obtained.

An inner casing 46 (Fig. 2) of sheet metal or the like is arranged with its lower portion telescoped over the upper part of the skirt 27 of the cover, this casing 46 enclosing the motor and with the outer casing member 21 defining an annular, upwardly converging chamber 47 leading to the delivery opening 23.

When the device is operated, assuming that liquid is in the lower part of the receptacle 10, the rotation of the cone 36 draws liquid up and distributes it onto the undersurface of the disk 35. The rapid rotation of the latter, for example at a speed of the order of from 3,000 to 3,500 R. P. M., causes the film of liquid to move out centrifugally, gradually getting thinner and thinner until it flies off from the edge of the disk at very high velocity and impacts the surfaces of the vanes 40, whereby it is broken down into fog or vapor. The rotation of the blades 43 creates a strong and powerful current of air which picks up the vapor and sweeps it out through the passages 41. Since these passages are of substantial length, they are effective in insuring a direction of delivery such that the escaping vapor-laden air is substantially freed from the drag effect of

the rotating disk and shows little tendency to swirl within the chamber 47. Apparently it moves almost vertically through the chamber 47, the individual streams delivered from the passages 41 merging as they approach the opening 23. Apparently but little friction is developed between the flowing moisture-laden air and the walls of the passage 47, as compared with prior devices in which the moisture-laden air takes up a rapid swirling action. The moisture-laden air thus emerges smoothly and at substantial velocity and with no observable tendency to rotate or swirl. Although the apparatus operates at high speed, very little noise can be discerned. From the opening 23 a smooth-flowing, substantially uniform current of moisture-laden air moves upwardly in a substantially vertical direction and substantially devoid of any swirling action.

This smoothly flowing stream, whose energy is not dissipated by the internal friction resulting from swirls or eddies, is projected much further from the orifice 23 than would be true if the current were of a swirling, irregular nature. Thus the vapor of fog is brought into contact with a very large volume of air with consequent optimum moistening effect. Moreover, because of this rapid and unimpeded flow the amount of water converted into fog or vapor is greatly increased, as compared with that resultant from the operation of apparatus in which the flow is impeded by friction, so that it becomes possible to deliver large quantities of water in vapor form by the use of apparatus of relatively small dimensions.

Not only is the apparatus useful for moistening the air, but it is also useful in distributing medicaments, germicides or odor dispellants. When designed for such purposes the parts which contact the liquid or vapor should be unaffected by the substances employed; for example, they may be of a synthetic plastic, or metal coated with enamel.

While one desirable embodiment of the invention has been described by way of example, it is to be understood that the invention is broadly inclusive of all modifications falling within the scope of the appended claims.

I claim:

1. Humidifying apparatus of the kind having in combination a receptacle for liquid, a circular, substantially flat disk rotatable about a vertical axis, a downwardly-tapering conical feed boss depending from the center of the disk into the liquid in the receptacle, a stationary cover member arranged above the disk, the cover member constituting a support for a motor, said cover member having a cylindrical, depending skirt portion of an internal diameter greater than that of the disk and whose lower edge is below the plane of the lower surface of the disk, said cylindrical skirt portion having a multitude of delivery passages therethrough whose walls are defined by fixed, immovable, substantially flat vanes constituting integral parts of said skirt portion, means beneath the disk operative to discharge air out through said passages, and a motor for rotating the disk at high velocity, characterized in that the vanes are so arranged as to provide delivery passages having side walls which terminate outwardly beyond the outer peripheral surface of the skirt, that side wall of each passage which is opposed to the direction of rotation of the disk and which is impinged by liquid centrifugally expelled from the disk being inclined at an angle of from 3° to 10° to that radial plane of the disk.

which intersects the inner vertical edge of said wall.

2. Humidifying apparatus of the kind having in combination a receptacle for liquid, a circular, substantially flat disk rotatable about a vertical axis, a downwardly-tapering conical feed boss depending from the center of the disk into the liquid in the receptacle, a stationary cover member arranged above the disk, the cover member constituting a support for a motor, said cover member having a cylindrical depending skirt portion of an internal diameter greater than that of the disk and whose lower edge is below the plane of the lower surface of the disk, said cylindrical skirt portion having a multitude of delivery passages therethrough whose walls are defined by fixed, immovable, substantially flat vanes, air-impelling blades below the disk operative to discharge a current of air outwardly through said passages, and a motor for rotating the disk at high velocity, characterized in that the vanes extend both inwardly and outwardly from the annular skirt portion, that face of each vane which is opposed to the direction of rotation of the disk and which is impinged by the liquid centrifugally expelled from the rotating disk being inclined at an angle of from 3° to 10° to that radial plane of the disk which intersects the inner vertical edge of said face, the outwardly-projecting portions of the vanes being of the order of $\frac{1}{16}$ inch in horizontal width measured outwardly from the outer surface of the skirt.

3. Humidifying apparatus of the kind having in combination a receptacle for liquid, a substantially flat disk rotatable about a vertical axis, a downwardly-tapering conical feed boss depending from the center of the disk into the liquid in the receptacle, a stationary cover member arranged above the disk, the cover member constituting a support for a motor, said cover member having a cylindrical depending skirt portion of an internal diameter greater than that of the disk and whose lower edge is below the plane of the lower surface of the disk, said cylindrical skirt portion having a multitude of delivery passages therethrough whose walls are defined by fixed, immovable, substantially flat vanes constituting integral parts of said skirt portion, fan blades attached to the under side of the disk and which are operative to discharge air outwardly through said passages, and a motor for rotating the disk at high velocity, characterized in that the vanes extend both inwardly and outwardly from the annular skirt portion, that face of each vane which is opposed to the direction of rotation of the disk and which is impinged by the liquid centrifugally expelled from the rotating disk being inclined at an angle of from 3° to 10° to that radial plane of the disk which intersects the inner vertical edge of said face, the outwardly-projecting portions of the vanes being of the order of $\frac{1}{16}$ inch in horizontal width measured outwardly from the skirt portion and the inner portions of the vanes being approximately $\frac{1}{8}$ inch in horizontal width measured from the inner periphery of the skirt portion.

4. Humidifying apparatus of the kind having in combination a receptacle for liquid, a circular, substantially flat disk rotatable about a vertical axis, a downwardly-tapering conical feed boss depending from the center of the disk into the liquid in the receptacle, a stationary cover member arranged above the disk, the cover member constituting a support for a motor, said cover member having a cylindrical depending skirt portion

5 of an internal diameter greater than that of the disk and whose lower edge is below the plane of the lower surface of the disk, said cylindrical skirt portion having a multitude of delivery passages therethrough whose walls are defined by fixed, immovable, substantially flat vanes, a fan beneath the disk and rotatable therewith, said fan being operative to discharge air outwardly through said passages, and a motor for rotating the disk at high velocity, characterized in that each vane is inclined at an angle of between 3° and 10° to that radial plane of the disk which intersects the inner vertical edge of the face of the vane which is opposed to the direction of rotation of the disk and which is impinged by the liquid which is centrifugally expelled by the rotating disk.

5. Humidifying apparatus of the kind having in combination a receptacle for liquid, a circular, substantially flat disk rotatable about a vertical axis, a downwardly-tapering conical feed boss depending from the center of the disk into the liquid in the receptacle, a stationary cover member arranged above the disk, the cover member constituting a support for a motor, said cover member having a cylindrical depending skirt portion of an internal diameter greater than that of the disk and whose lower edge is below the plane of the lower surface of the disk, said cylindrical skirt portion having a multitude of air and water passages therethrough whose walls are defined by fixed, immovable, substantially flat vanes constituting integral parts of said skirt portion, a motor for rotating the disk at high velocity, and a plurality of fan blades fixed to the underside of the disk, the blades being disposed symmetrically about the axis of the disk, characterized in that each vane is inclined at an angle of approximately $6\frac{1}{2}^{\circ}$ to that radial plane of the disk which intersects the vertical inner edge of the face of the vane which is opposed to the direction of rotation of the disk and which is impinged by the liquid centrifugally expelled from the disk.

6. Humidifying apparatus of the kind having in combination a shallow basin-like receptacle for liquid, said receptacle having an upstanding side wall provided with air ingress apertures, a casing comprising an annular bottom member supported on the side wall of the receptacle, the casing also comprising an upper part whose lower margin removably fits the outer part of the bottom member of the casing, the upper part of the casing tapering upwardly and terminating at a delivery orifice, a circular, substantially flat disk located in a plane just above the plane of the top of the receptacle wall, said disk being rotatable about a vertical axis, a feed boss depending from the center of the disk into the liquid of the receptacle, a stationary cover member arranged above the disk, the cover member constituting a support for a motor, said cover member having a cylindrical, depending skirt portion of an internal diameter greater than that of the disk and whose lower edge is below the plane of the lower surface of the disk, said cylindrical skirt portion having a multitude of passages therethrough whose walls are defined by substantially flat vanes constituting integral parts of said skirt portion, a motor for rotating the disk at high velocity, an inner casing having its lower portion telescoped over the upper part of the skirt portion of the cover, the inner casing housing the motor and being spaced from the upper part of the outer casing to provide an annular chamber leading from the vanes to the delivery orifice, said outer chamber

being free from baffles or other obstructions to free vapor flow, each vane being inclined at an angle of from 3° to 10° to that radial plane of the disk which intersects the inner vertical edge of that face of the vane which is opposed to the direction of rotation of the disk and which is impinged by the liquid centrifugally expelled from the disk, whereby the water vapor emerging from between the vanes is devoid of appreciable tendency to swirl or rotate.
